CLAIM

The ornamental design for a container for storing and dispensing two beverages, as shown and described.

DESCRIPTION

FIG. 1 is a front perspective view of a container for storing and dispensing two beverages, showing my new design;

FIG. 2 is a back perspective view thereof;

FIG. 3 is a front view thereof;

FIG. 4 is a left view thereof;

FIG. 5 is a right view thereof;

FIG. 6 is a back view thereof;

FIG. 7 is a top view thereof; and,

FIG. 8 is a bottom view thereof.

The dash-dash broken lines depict perforated portions of the container for storing and dispensing two beverages that form part of the claimed design. The dot-dash broken lines in the drawings depict portions of the container for storing and dispensing two beverages that form no part of the claimed design.

1 Claim, 6 Drawing Sheets
